UNITED STATES PATENT OFFICE.

REINHOLD HERMAN, OF CRAFTON, PENNSYLVANIA.

PRINTING APPARATUS.

SPECIFICATION forming part of Letters Patent No. 743,160, dated November 3, 1903.

Application filed March 28, 1903. Serial No. 149,925. (No model.)

To all whom it may concern:

Be it known that I, REINHOLD HERMAN, a citizen of the United States of America, residing at Crafton, in the county of Allegheny and 5 State of Pennsylvania, have invented certain new and useful Improvements in Printing Apparatus, of which the following is a specification, reference being had therein to the accompanying drawings.

This invention relates to certain new and useful improvements in printing apparatus, and relates more particularly to devices adapted for the reproduction of negatives by the aid of artificial light—such, for instance, as 15 electric light.

The invention has for its object the construction of a machine or apparatus having a printing-cylinder adapted to support the negatives to be reproduced, a lamp mounted stationary in said cylinder, with means to automatically extinguish the light of said lamp at a predetermined time, together with means for regulating or controlling the extinguishing of said lamp.

Heretofore and before my invention it has been the practice to employ a transparent cylinder into which a lamp (generally an electric lamp) is lowered, and when the lamp in its descent reaches a predetermined point a 25 switch or other cut-out automatically operates to cut out the light. The lamp is then returned to its normal or elevated position above the cylinder in order that the negatives may be removed and others placed in 30 position on the cylinder. An invention of this principle is involved in my application, filed October 1, 1901, Serial No. 77,192, and also in my prior patent, issued February 17, 1903, No. 721,041. In this patent referred to, how-

ever, while I employ a vertically-movable lamp, the latter is adapted to be returned to its elevated or normal position before the current is cut off from the lamp. In my present invention, however, while I employ a glass or 45 other transparent cylinder and preferably mount the same on trunnions, so that the same may be revolved in order to facilitate the placing and removal of the negatives on and from the cylinder, I dispense with the 50 movable lamp and mount the lamp stationary in the cylinder, the only movement imparted to the same being that of uniform

movement with the cylinder when the latter is revolved either to place negatives thereon or remove same from the cylinder.

The present invention also contemplates other improvements in the art of reproducing drawings, photographs, printed matter, &c., by the aid of artificial light, and these, together with the improvements enumerated, 60 will be hereinafter more specifically described and then particularly pointed out in the appended claims, and in describing the invention in detail reference will be had to the accompanying drawings, forming a part 65 of this application, and wherein like numerals of reference will be employed for indicating like parts throughout the different views of the drawings, in which—

Figure 1 is a side elevation of my improved 70 printing apparatus with the printing cylinder or frame in the upright or printing position. Fig. 2 is a side elevation of the same, showing the circuit from the motor to the lamp. Fig. 3 is an enlarged central vertical 75 sectional view of the rotary circuit-connector, showing the lamp in side elevation and in diagram the circuit from the motor through the lamp, the automatic switch being removed. Fig. 4 is a side elevation of the cut-out, its support-board, the lamp, and the circuit therewith with the rotary circuit-connector removed and showing the dash-pot in central vertical section. Fig. 5 is a top plan view of the printing frame or cylinder. Fig. 80 85 6 is a detail perspective view of portions of the lamp and the securing means therefor. Fig. 7 is a vertical sectional view of the supporting-board for the counterbalance-weight attached to the plunger-rod, showing a portion 90 of said rod and the rewinding mechanism therefor in side elevation.

In my present invention I prefer to mount transparent cylindrical printing-frame 1 in such a manner that the same may be revolved whereby it may be placed horizontally in order to facilitate the placing of the negatives or other matter thereon and the removal of the same therefrom after printing. However, it is to be noted that in connection 95 with my present invention, which involves the mounting of a lamp stationary in the cylinder, that this cylinder or printing-frame could be made non-rotatable—that is, adapted 100

to remain in the vertical position at all times. I will, however, describe the same in connection with a means for rotating the cylinder, which is the preferred form of construction, 5 and to accomplish this I provide a pair of standards or uprights 2, connected together by tie-rod 3, and in bearings 4 4' at the upper end of which are mounted trunnions 5 5', which carry angle-bar clamps 6, adapted to 10 engage with the angle-bar uprights 7, which support the cylindrical printing-frame. This cylindrical printing-frame is provided with suitable means for clamping the negative or other matter in position on the cylinder or 15 frame for reproduction, this means embodying an apron adapted to be wrapped around the printing-frame after the matter to be reproduced has been placed thereon. The manner of securing this apron to the printing cylinder or frame and the manner of fastening the same were fully shown and described in my Letters Patent No. 721,041, heretofore referred to, and has hence not been shown in this application in detail, as the same form 20 of construction illustrated and claimed in said patent is preferably employed by me in connection with the present device. Mounted in the cylinder or printing-frame centrally thereof is a printing-lamp, preferably of the 25 vapor-lamp form, and this lamp extends the length of the printing-cylinder or the length of so much of the cylinder as is employed for the printing-surface. The lamp 8 is provided with a neck 9 at each end, on which is placed 30 a sleeve or collar of insulation 10. The insulated sleeve or collar 10 fits in a seat 11, provided therefor in the cross-bar 12, affixed to the end rings 14 of the support for the cylindrical printing frame or cylinder, the cross- 35 bar 12 at each end of the cylinder carrying segmental-shaped flanges 15 to receive the flange 16, carried by the collar 17, which fits over the flange 15 and over the insulated neck of the lamp and is fastened by set-screw 18 or other suitable means. Binding-posts 19 20 are in the respective ends of the lamp for securing the circuit-wires, as will be herein- 40 after more fully described and pointed out. The trunnion 5' is provided with a bar 21 therethrough to receive the circuit-wires, and this trunnion 5' is extended some distance beyond the bearing 4', (see Fig. 3,) and on this 45 extended portion of the trunnion is mounted the brass or like bushing 22, secured in position by screws 23 passing through the integral collar 24 at the inner end of said sleeve 22. Mounted on this bushing 22 is an insulated sleeve 25, and on said insulated sleeve 25 are mounted the contact-rings 26 27, which 50 are suitably spaced apart and are insulated from each other by the insulated sleeve 25 and are also insulated from the trunnion or bearing by insulation-washers 28. These contact-rings and the insulation-washers are 55 secured in position by means of the washer 29, which is placed against the opposite washer 28 and held by jam-nut 30, threaded onto the end of the bushing or sleeve 22. The bearing 4' carries an arm or extension 31, in which is mounted a stud or post 32, securely held by jam-nuts at each side of the arm or extension 31. This stud or post 32 has mounted thereon a brass or other bushing or sleeve 33, on which is placed the insulated sleeve 34, and mounted on this insulated sleeve 34 are the clips 35 36, respectively, for engagement with the contact-rings 26 27. These parts are held on the stud or post 32 by means of the jam-nut 37. This construction just described constitutes a rotary circuit-connector for the purpose of allowing the cylinder, lamp, and wires thereof to be rotated without the breaking of the conductors. Attached to the standard 2, carrying the bearings 4', is the insulation-base 38, on which the 60 cut-out or switch for extinguishing the lamp at a predetermined time is mounted. This cut-out or switch is of the same form of construction as that shown and described in detail in my prior patent, No. 721,041, embodying a binding-post 39 with fuse 40, connecting with spring-clip 41 to form a contact through the sector-shaped knife 42 with spring-clip 43. The knife 42 is secured to insulation-disk 44, carried on the brass trunnion 45. This brass trunnion 45 revolves in a bushing (not shown) which is fastened to the insulated base 38. To this trunnion 45 is secured a lever 46, attached thereto by means of screws or in any other suitable manner. On the insulated base 38 there is also fastened a stud 47, to which is secured one end of the spring 48, the other end of said spring being connected to the lever 46 near its free end. Attached to this lever 46 at the outer 70 or free end thereof is a cord, chain, or other suitable device 49 for the purpose of operating the lever so as to actuate the trunnion 45 and cause the notch 50 in said trunnion to be engaged by the pawl 51, carried on the end of the trip-lever 52, pivotally mounted on the insulated base and provided at its outer end with an eye 53 to receive the vertically-movable rack-bar 54. This rack-bar 54 is preferably made in the form of a tube and is extended into a dash-pot cylinder 55, being provided at its lower end with a valve-seat 56. Threaded onto the tube within the cylinder 55 is a plunger 57, having ports 58, and on which plunger rests the valve 59 for normally closing said ports. This cylinder 55 is affixed to the standard 2 by means of straps 60 or by any other suitable means and is adapted to receive a liquid, preferably oil. The tube forming the rack-bar 54 is extended through 80 a suitable stuffing-box 61, and through this tube is extended a valve-rod 62, provided on its lower end with a valve 63 to engage with the seat 56. The hollow tube 54, which forms the plunger-rod or piston-rod, is provided with 85 ports 64 above the vertically-movable valve 58. The valve-rod 62 is provided at its upper end with a head 65, located within the open frame 66, to which the upper end of the

rack-bar 54 is connected. This frame 66 is also attached to a cord, chain, cable, or like connection 67, which passes over the pulley 68, journaled in brackets 69 on the front face 5 of the supporting base or board 70, near the upper end thereof, and over a pulley 71, journaled in brackets 72 on the rear face of said supporting-board 70, at the upper end thereof, and carries a counterbalance-weight 73. Attached to this supporting board or base 70, on the front face thereof, is a pair of brackets 74, in which is journaled the pinion 75 to engage with the rack 76 of the combined rack-bar and plunger-rod 54. One end of the shaft 15 on which the pinion 75 is mounted is adapted to receive a crank 77 for returning the plunger and rack-bar to its elevated normal position, where it is held by means of a pawl 78 and ratchet-wheel 79, the pawl being carried 20 by one of the brackets 74 and the ratchet-wheel being mounted on the shaft which carries the pinion 75.

The trip-lever 52 is actuated at a predetermined time whereby to disengage the pawl 25 51 thereof from engagement with notch 50 of bushing 45, whereby spring 48 will operate lever 46, bushing 45, and knife 42 by means of an adjustable trip or stop 80, carried by the hollow plunger-rod forming the rack-bar 30 54. The knife 42 is limited in its movement in the direction in which it is moved by spring 48 by a stop 81, carried by the insulation-base 38.

To describe the circuit, reference will be 35 had particularly to Fig. 3 of the drawings, in which, in connection with the sectional view of the rotary circuit-connector, there is shown a diagrammatical view of the circuit from the motor to the switch or cut-out, over the rotary 40 circuit-connector, through the lamp, and back to the motor. With the switch or cut-out in the closed position—that is, with the knife 42 in engagement with clips 41 43—the circuit would be as follows: from the motor 82, over conductor 83, to binding-post 39 on the insulation-base 38, over fuse-wire 40, to spring-clip 41, over knife 42, to spring-clip 43, over conductor 84, to clips 35 of the rotary circuit-connector, from said clips 35, over contact- 45 ring 27 of the rotary circuit-connector to conductor 85, attached to said contact-ring. This conductor is passed through an opening 86, provided therefor in the contact-ring 26, the walls of which opening are insulated, said 50 conductor being then carried through the bore 21 in the trunnion 5' and connected to binding-post 20 of the lamp 8. The circuit is thence through the lamp to binding-post 19 on the other end thereof, and by conductor 55 87 from said binding-post 19, through the hollow trunnion 5' to the contact-ring 26, across spring-clips 36 and over conductor 88, to motor 82.

I will now describe briefly the operation of 60 the device when the parts are assembled as shown in the accompanying drawings and as

heretofore described. The cylinder or printing-frame is placed in a substantially horizontal position, where it may be locked by a suitable locking device 89. (Shown and described in detail in my Patent No. 721,041.) The negative or matter to be reproduced is then placed on the cylinder, where it is secured by means of the binding-apron carried by cylinder or printing-frame. The cylinder or printing-frame is then returned to its vertical position and the cord, chain, or other connection pulled downwardly, which rotates bushing 45, whereby to throw knife 42 into engagement with clip 41, and thereby completing the circuit through the lamp, as heretofore described. When lever 46 is pulled downwardly, pawl 51 of the trip-lever 52 engages in notch 50 of the bushing 45 to hold the knife 42 in engagement with clip 41 85 to maintain the circuit. The pawl 78 being released from ratchet 79, counterweight 73 moves downwardly, drawing piston 57 upwardly, the liquid contained in cylinder 55 above the piston 57 feeding through ports 64 90 and out through the hollow piston-rod at the lower end thereof in proportion according to the amount that the valve 63 has been opened to permit. On the ascent of the hollow plunger-rod the stop 80 engages with the trip-lever 95 52, elevating the outer end of said lever, whereby to disengage pawl 51 thereof from engagement with notch 50 in bushing 45, which allows spring 48 to actuate lever 46 and partially rotate bushing 45, throwing 100 knife 42 out of engagement with clip 41 and breaking the circuit to extinguish the light. The counterweight is returned to its normal position by means of crank 77, the elevating of the counterweight moving the hollow plunger-rod and rack-bar downward, this descent of the plunger 57 being permitted by reason of the valve 59 rising under the pressure of the liquid, so as to permit the latter to flow upwardly through ports 58 into the upper 105 part of the cylinder 55.

It is to be noted that stop 80, being adjustable on the hollow plunger-rod and rack-bar, may be so positioned as to cut out the light at any time desired, giving a range of 110 from a few seconds up to any number of minutes that may be required, according to the nature of the work that is being reproduced.

Although I have shown and described the stationary lamp in connection with a rotatable cylinder, as I prefer this form of mounting the cylinder, owing to the convenience obtained thereby for the placing of the matter to be reproduced in position on the cylinder and the removal therefrom of the same, yet 120 I do not wish to limit myself to the employment of a rotatable cylinder in connection with a stationary lamp, as it will be observed that the same circuit, as herein shown and described, may be employed with a cylinder 125 or printing-frame adapted to remain in the vertical position or with a cylinder mounted

stationary in a horizontal position or other position of the cylinder, as might be required, according to the particular location in which it was desired to place the machine.

5 It is also to be noted that while I have herein shown and described a preferred form of construction in connection with the rotatable circuit-connector, the switch mechanism, the controlling mechanism, and in other details, 10 yet I do not wish to confine myself to the specific construction shown and described, as it will be apparent that various changes may be made in the details of construction without departing from the general spirit of the invention.

Having fully described my invention, what I claim as my invention, and desire to secure by Letters Patent, is—

1. In combination with a transparent printing-cylinder, a lamp mounted in said cylinder, an electrical circuit in connection with said lamp, and means for automatically breaking said circuit at a predetermined time, substantially as described.

25 2. In combination with a rotatable printing-cylinder, a lamp mounted within the cylinder, and rotatable in unison therewith, an electrical circuit in connection with said lamp, and means for automatically breaking said 30 circuit at a predetermined time.

3. In combination with a printing-cylinder, a printing-lamp mounted within the cylinder and movable in unison therewith.

4. In a printing apparatus, a trunnioned 35 printing-cylinder, and lamp-holding means on the ends of said cylinder, in combination with a lamp extending the length of the cylinder within the same and secured in said holding means.

40 5. In a printing apparatus, a trunnioned printing-cylinder rotatable endwise in its trunnions, and a printing-lamp removably mounted within the cylinder and remaining stationary therein during the printing operation.

45 6. In a printing apparatus, a transparent printing-cylinder mounted to be rotated end over end, in combination with a printing-lamp mounted within the cylinder and extending from end to end thereof.

7. In a printing apparatus, a printing-cylinder, an electrical lamp mounted within the cylinder, an electrical circuit in connection with said lamp, a rotary circuit-connector 55 in said circuit, and means for automatically breaking the circuit at a predetermined time, substantially as described.

8. In a printing apparatus, a printing-cylinder, a lamp within the cylinder, and means 60 for automatically extinguishing the light of

said lamp at a predetermined time, substantially as described.

9. In a printing apparatus, a printing-cylinder, a printing-lamp remaining at all times in the same relative position with respect to 65 the cylinder, and means to automatically discontinue the printing process.

10. In a printing apparatus, the combination with a printing-cylinder, of a printing-lamp mounted centrally within the cylinder 70 and held at the ends, an electrical circuit in connection with said lamp, and means for automatically discontinuing the printing process.

11. In a printing apparatus, a rotatably-mounted printing-frame, a lamp mounted 75 within said frame and rotatable therewith, and means for discontinuing the printing process at a predetermined time.

12. In a printing apparatus, a rotatably-mounted printing-frame, a lamp mounted 80 within said frame, bars mounted in the ends of the frame in which said lamp is detachably held, and means for automatically extinguishing the light of said lamp to discontinue the printing process.

85 13. In a printing apparatus, a rotatable printing-frame, a lamp mounted therein and rotatable in unison with the frame, and a switch to automatically extinguish the light of said lamp at a predetermined time.

14. In a printing apparatus, a printing-cylinder, a lamp mounted within the cylinder and extending from end to end of the same, and a switch for automatically extinguishing the light of said lamp at a predetermined 90 time.

15. In a printing apparatus, a printing-cylinder, an electric lamp mounted in said cylinder, an electric circuit to said lamp, and controlling means including a fluid-regulating cylinder and a switch, the latter to automatically break the circuit on the completion of the printing process.

16. In a printing apparatus, a rotatably-mounted printing-cylinder, supports in which 105 the cylinder is mounted, a lamp in said cylinder, and means supported on the frame or standards for controlling the circuit.

17. In a printing apparatus, a rotatably-mounted printing-frame, supports on which 110 the frame is mounted, a lamp rotatable in unison with said frame, and controlling means for the lamp mounted on the support of the frame, substantially as described.

In testimony whereof I affix my signature 115 in the presence of two witnesses.

REINHOLD HERMAN.

Witnesses:
